UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,252,308.

Specification of Letters Patent.

Patented Jan. 1, 1918.

Original application filed March 9, 1916, Serial No. 83,146. Divided and this application filed November 7, 1916. Serial No. 130,047.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in stay bolt structures for boilers and more particularly to means for testing the integrity of the stay bolts of boilers,—this application being a division of an application for patent filed by us on the 9th day of March, 1916, and designated by Serial No. 83,146.

The object of our present invention is to provide simple and efficient means which shall be accessible for testing purposes without removing any part of connecting means for the bolt.

In the accompanying drawings; Figure 1 is a sectional view showing an embodiment of our invention and Figs. 2, 3, 4, 5, 6 and 7 are views illustrating modifications thereof. 30 1 represents an outer boiler sheet having a hole for the accommodation of a bearing sleeve 2,—said sleeve being externally threaded at 3 to screw into the hole in the boiler sheet and the upper or outer portion 35 of the threaded sleeve receives the internally threaded portion of a cap 4, the latter being also formed with a shoulder 5 which may rest against the end of the sleeve 2. The sleeve 2 is formed interiorly with a seat 6 40 for the rounded or spherical head 7 of a stay bolt 8 and said head is made with a slot 9 to receive the tongue 10 of a driving member 11.

In the embodiment of our invention illustrated in Fig. 1, the cap 4 is made with a central enlargement 12 having an opening therein formed with curved walls to provide a partly spherical seat 13 for the spherical body of the rotary or driving member 11,— 50 the latter also being provided with an angular portion or head 14 to receive a wrench.

The purpose of our invention is to provide readily accessible means whereby a turning force may be applied to a stay bolt

without removing the cap or any part of 55 the attaching means for the bolt, so that it may be at once determined whether the bolt is broken. When the bolt is to be tested, the operator will apply a suitable wrench to the angular head 14 of the driving member 60 11 and apply a force thereto tending to turn said driving member, such force being transmitted to the bolt through the medium of the tongue 10 of said driving member which enters the slot in the bolt head. 65 Should the said driving member refuse to turn, this fact will indicate that the bolt is whole, but should said member turn when rotary force is applied thereto, this fact will at once indicate that the bolt is broken. 70

Fig. 2 shows a construction similar to that shown in Fig. 1, except that in Fig. 2, the cap is made in two parts 15, 16 screwed together.

In Fig. 3, a hemispherical cap 17 is shown, 75 and this is provided with an opening 18 for the accommodation of the rotary or driving member 19, the latter being formed with a convex portion 20 bearing against the inner face of the cap and with a threaded portion 80 21 to receive a nut 22 having a concave face to rest against the outer convex face of the cap. The outwardly projecting portion 21 may be provided with a slot 23 to receive a screw driver. 85

The construction shown in Fig. 4 embodies a cap 24 having an angular exterior with a flat outer face and a nut 25 on the rotary or driving member 26 rests against said flat outer face of the cap. 90

In the construction shown in Fig. 5, the cap 4 is made with a comparatively large central opening closed by a rotary or driving member 27 having a beveled portion 28 bearing against the inner face of the cap 95 and provided with a tongue 29 to engage the slot of the bolt head. A ring or washer 30 encircles the neck portion of the member 27 and rests against the cap 4. The member 27 is provided with bendable lugs 31 100 which are made to engage the ring 30, and thus said member is coupled to the cap 26. A central enlargement 32 is provided on the rotary or driving member 27 to receive a tool for turning the same. 105

In the form of the invention shown in Figs. 6 and 7, the rotary driving member is made with a head 33 having a shoulder 34,

and a driver slot 35. A split ring 36 is disposed between the shoulder 34 of the head 33 and the cap 37.

Various other changes might be made in the details of construction of our invention without departing from the spirit thereof or limiting its scope and hence we do not wish to restrict ourselves to the precise details herein set forth except as defined by the scope of the appended claims.

Having fully described our invention what we claim as new and desire to secure by Letters Patent, is:—

1. A stay bolt structure comprising a stay bolt, a cap over the end of the same, and a rotary member having a part disposed within the cap and operatively associated with the bolt head, and said rotary member having a part projecting outwardly beyond the cap and adapted for the reception of a tool for applying rotary force to said member.
2. A stay bolt structure comprising a stay bolt having a slotted head, a cap over said head, a rotary member having a part projecting through the cap for the reception of a tool, and said rotary part having a tongue to engage the slotted head.
3. A stay bolt structure comprising a stay

bolt having a slotted head, a cap over said head, and a rotary member having a part engaging the cap and a part to engage in the slot in the bolt head, the last-mentioned part of the rotary member and the slot in the bolt head being so relatively proportioned that the bolt may have longitudinal and lateral movement independently of said rotary member.

4. In a stay bolt structure, the combination with a stay bolt, and a cap over the end of the same, of means within said cap and rotative independently thereof for applying rotary pressure to the bolt.

5. In a stay bolt structure, the combination with a stay bolt, and a cap over the end of the same, of means within said cap and rotative independently thereof for applying rotary pressure to the bolt, said means having a tool receiving part which is accessible without removal of the cap.

In testimony whereof, we have signed this specification in the presence of two subscribing witnesses.

BENJAMIN E. D. STAFFORD.
ETHAN I. DODDS.
